UNITED STATES PATENT OFFICE.

ANDREW SMITH, OF CHICAGO, ILLINOIS.

WOOD-PLATE-CUTTING MACHINE.

SPECIFICATION forming part of Letters Patent No. 706,349, dated August 5, 1902.

Application filed October 16, 1901. Serial No. 78,800. (No model.)

To all whom it may concern:

Be it known that I, ANDREW SMITH, of Chicago, in the county of Cook and State of Illinois, have invented certain new and useful 5 Improvements in Wood-Plate-Cutting Machines; and I hereby declare that the following is a full, clear, and exact description thereof, reference being had to the accompanying drawings, which form part of this specification.

My invention relates to machines for cutting plates in a single unjoined piece from blocks of wood.

The object of my invention is to provide an 15 improved machine for cutting wooden plates from a block of wood, wherein a completed plate may be cut by one operation, the plate when falling from the block being complete within itself without joint and without further manipulation being necessary for finishing it, the product of the machine being a 20 plate or dish made of wood approximately convexo-concave, but having a flat bottom part, the entire body being made of a single 25 piece and finished by one operation of the machine.

Another object of my invention is to provide a machine having rigid construction and positively-operating parts, whereby the cutting-off knife will perform its work smoothly and without chattering in the performance 30 of its function and whereby the facing-knife will perform its work without interfering with the operation of the cutting-off knife.

35 My invention consists in the novel constructions, combinations, and arrangements of the parts, as hereinafter more fully described, and specifically pointed out in the appended claims.

40 In the drawings which form a part of this specification, Figure 1 is a side elevation. Fig. 2 is a front elevation of the same, part being shown in section. Fig. 3 is a plan view of the machine. Fig. 4 is a vertical longitudinal sectional view. Fig. 5 is a side elevation of the machine, part of the frame being broken away for the purpose of showing the cam. Fig. 6 is a section taken on line 45 6 of Fig. 5, showing the guides for the two knives made into the respective housings of the machine. Fig. 7 is a section through a

plate or dish which is a product of this machine.

In all of the views the same characters of reference indicate corresponding parts. 55

A and A' are the housings for the bearings of the shafts, which constitute part of the frame of the machine.

B is a table for supporting the block of wood F, from which the dishes are cut. 60

C is a main driving-shaft, and C' is an intermediary or counter shaft.

C² is the main driving-pulley, attached to the shaft C. C³ is the balance-wheel, which is also fixed to the said shaft. 65

Two gear-wheels (indicated by C⁴) are attached to the shaft C on the outer side of the respective housings for the purpose of transmitting the power from the said shaft to the cutting-off knife D⁴, and two similar gear-wheels C⁶ are fixed to the shaft C' and mesh into the former gear-wheels for the purpose of transmitting the power from the said shaft to two other gear-wheels C⁷, which mesh into the gear-wheels C⁶ and are shiftingly carried 70 by the arms c' and c², arranged on either side of the housings A and A'. They have bearings on the extended ends of the shafts C and on the ends of the shafts C¹⁰, by which the gear-wheels C⁷ may be partially rotated around 75 the shaft C'. Gear-wheels C⁸ are fixed to the small shafts which extend through the respective housings and which have journal-bearings in vertically-moving blocks. These bearings are adapted to slide vertically in slots 80 or ways a, made in the respective housings. Vertically-reciprocating rods D may be made 85 a part of the said journal-bearing blocks, which carry the shafts C¹⁰, or they may be made separately and connected thereto. The 90 said connecting-rods are shown to be partly contained within guiding-grooves formed into the sides of the housings A and A'. These rods are provided on their lower ends with inwardly-extending pins d⁸, which have rollers d⁴ on the outer ends thereof. These rollers project into cam-slots c, made into the cam-wheels C⁵.

The rods D are adapted to be vertically reciprocated within the guide-slots by means 95 of the cam c, and when these rods, which are adapted to be moved coincidently with refer-

ence to time and extent, are reciprocated thereby they are the means by which the location of the cutting-off knife D⁴ is changed with reference to its vertical position. The 5 cutting-off knife D⁴ is connected at either end into clamps d², which are the inner terminals of the knife-shaft C¹⁰.

The arrows around the outside of the various gear-wheels show their respective direction of rotation.

A facing-knife D⁵, adapted to be vertically reciprocated, is located just in front of the cutting-off knife or between the center of the shaft which revolves the cutting-off knife and 15 the block of wood to be operated upon. The facing-knife is held in a frame composed of two vertical side pieces D² and a longitudinal bottom piece D³, joining the said side pieces. The latter is connected by a pitman-rod D³ to 20 a crank-arm D' of the shaft C. Instead of the crank-arm D' a cam, eccentric, or any convenient means for imparting reciprocating motion to the knife-frame may be employed.

25 The operation of my device is as follows: In Fig. 4 the knives D⁴ and D⁵ have arrived at the position shown. The crank-arm D' is about to advance in the direction shown by the arrow of the wheel C⁸. The frame D², 30 containing the facing-knife D⁵, in which the latter is shown located just above the block F, will be drawn down by means of the pitman-rod D³. The frame is adapted to be reciprocated in a vertical direction in the ways 35 or guides made into the respective housing-plates. The cutting-off knife D⁴ will advance first and complete practically one-fourth of a revolution, cutting the block from f to f'. The knife D⁴ is stationary with reference to 40 its vertical movement during the time that the roller d⁴ remains in that portion of the cam-groove c, which is of even or uniform radius, located between the points indicated by the numerals 1 and 2 of Fig. 5. When 45 the point 2 arrives at the position shown within the vertical path of the roller d⁴, the crank-arm D' will have turned one-quarter of a revolution and the facing-knife D⁵ will have reached a position in the block F just 50 above that occupied by the cutting-off knife. The cutting-off knife D⁴ being rotated while the cam c is traveling the distance between the point 1 and the point 2, it will have been rotated practically one-quarter of a revolution. When the part of the cam c contained between the points 2 and 3 is passing by the roller d⁴ the side rods D will be drawn 55 downwardly, and thereby the blocks containing the shafts C¹⁰, to which the cutting-off 60 knife D⁴ is attached, will be correspondingly moved downwardly, and at the same time the rotative motion of the knife D⁴ will be practically suspended, owing to the fact that the vertical bodily movement of the gear-wheel C⁸ practically equals the rotative movement of the gear-wheel C⁷, and therefore 65 the knife will have only a vertical motion

imparted to it while traveling through the plane in the wood block indicated by f' and f², and for this reason it will cut a flat 70 bottom in the dish to be formed out of the block of wood F. When the point 3 of the cam arrives at a point in the vertical path of the roller d⁴, then the downwardly vertical movement of the knife D⁴ will have ceased, 75 owing to the fact that the part of the cam between the point 3 and point 4 is of uniform radius and that no reciprocating motion is thereby imparted to the knife; but the rotative motion of the knife will be resumed and 80 the region within the block contained between f² and f³ at the bottom of the plate will be cut in the shape shown in Fig. 7. While that part of the cam c contained between the points 4 and 1 passes the roller d⁴ the knife D⁴ will be 85 rotated and raised to its vertical position or one-half revolution, which is accomplished during the time that the cam is rotating through the last one-quarter of its revolution, or, in other words, the knife will be rotated 90 by the cam one-half of a revolution while the driving-shaft is being rotated only one-quarter of a revolution, for the reason that the vertical upward movement of the gear-wheels, 95 bearings, and knife will now become accelerated with reference to the speed of the gear-wheels C⁷ by the vertical motion coacting with the rotary motion to increase the speed of the wheels C⁸, and for this reason the cutting-off knife will travel the last half of the 100 revolution much more rapidly than the first half. I have shown a horizontal screw b and a knee-piece b' for advancing the position of the block F on the table B. This shaft may be rotated by any convenient or suitable 105 mechanism. It will be noticed that the cutting edge of the knife D⁴ is back of the axis of its rotation. This is necessary to prevent chattering as the knife passes through the wood. The shape of the knife D⁴ is shown 110 in the three views Figs. 2, 3, and 4. The dish from the block F is cut during the downward stroke of the knife. The upper curved portion of the dish is cut while the knife is traveling from the point f to the point f' 115 in a rotary direction. The rotary motion of the knife is then suspended and the vertical motion cuts the flat bottom or central portion of the dish contained between the points f' and f². Then the vertical motion of the 120 knife is suspended and the rotary motion is resumed, which carries the knife through the region contained between f² and f³, when the dish is completed. The facing-knife D⁵ then faces off the edge of the block F for the next 125 dish.

Many modifications may be made from the construction shown without departing from the true gist and spirit of my invention.

Having described my invention, what I 130 claim as new and useful, and desire to secure by Letters Patent of the United States, is—

1. In a plate-cutting machine a frame adapted to support a block from which the

product is to be cut, a cutting-off knife adapted to engage said block, a means for reciprocating said knife, and a means for rotating said knife and in connection with the reciprocating means for returning said knife to a position to begin another stroke within less time than that required to make the stroke.

2. In a plate-cutting machine a frame adapted to support a block from which the product is to be cut, a cutting-off knife adapted to engage said block, a means for reciprocating said knife, a means for rotating said knife and in connection with the reciprocating means for returning said knife to a position to begin another stroke within less time than that required to make the stroke, and a facing-knife adapted to face the block.

3. In a plate-cutting machine a revoluble cutting-off knife D^4 , shafts $C^{10} C^{10}$ to which opposite ends of said knife are attached, gear-wheels $C^8 C^8$ for rotating said shafts, bearing-supports for each of said shafts, adapted to be reciprocated, a means for reciprocating said bearing-supports, driving gear-wheels $C^6 C^6$ on a shaft common to both, interme-

diate shifting gear-wheels $C^7 C^7$ connecting the gear-wheels C^6 and C^8 , a means for holding said shifting gear-wheels in train while gear-wheels $C^8 C^8$ are being reciprocated.

4. In a plate-cutting machine a driving-shaft C' , housings in which said shaft is journaled, shafts $C^{10} C^{10}$, a revoluble cutting-off knife having opposite ends fixed to and connecting said shafts, vertically-reciprocating journal-bearings for each of said shafts C^{10} on said housings, guides in which said bearings are adapted to be reciprocated, means for coincidentally reciprocating said shafts, a driving-shaft C' , gear-wheels $C^6 C^6$ on opposite ends of said driving-shaft, and an intermediate train of gearing for transmitting rotary motion therefrom to the shafts $C^{10} C^{10}$.

In testimony that I claim the foregoing as my own I affix my signature in presence of two witnesses.

ANDREW SMITH.
